UNITED STATES PATENT OFFICE.

HERBERT W. EAKINS, OF SPRINGFIELD, OHIO.

CAKE-FORMING DEVICE.

1,176,949.

Specification of Letters Patent. Patented Mar. 28, 1916.

Application filed February 26, 1914. Serial No. 821,345.

To all whom it may concern:

Be it known that I, HERBERT W. EAKINS, a citizen of the United States, residing at Springfield, in the county of Clark and State of Ohio, have invented certain new and useful Improvements in Cake-Forming Devices, of which the following is a specification, reference being had therein to the accompanying drawing.

This invention relates to cake-forming devices and is designed more particularly for use with a device for forming pop-corn confections, which latter consist of pop-corn mixed with a suitable binder of syrup or the like and pressed into cake form.

The object of the invention is two-fold. The main purpose is to facilitate and expedite the formation of the cakes by performing the several operations in such a manner that the molds can be filled, the cakes formed ejected from the molds and discharged from the machine with a very small amount of labor and no handling after the filling of the molds, and that the formed cakes may have an opportunity to "set" or harden before they are discharged, thus preventing the cakes from being injured when they are discharged. A further purpose of the invention is to so construct the device as to render it very compact and to provide devices to automatically align the molds with the plungers which compress the material therein.

In the accompanying drawings, Figure 1 is a plan view of a device embodying my invention, partly broken away; Fig. 2 is a sectional view taken on the line $\alpha\alpha$ of Fig. 1; Fig. 3 is a sectional view of the upper portion of the apparatus showing the parts in position for ejecting the cakes from the mold; Fig. 4 is a similar view showing the mold refilled and in position to discharge the ejected cakes from the table; and Fig. 5 is a detail view of the bottom-plate.

In carrying out my invention I provide a work table having thereon and preferably near one end thereof a receptacle for the mass of material which is to be formed into cakes. Mounted on the table adjacent to the receptacle is the cake-forming device proper consisting of the molds and plungers which enter the molds to compress the cakes. The mold cavities are provided with a movable closure at their lower ends which will close the cavities during the compressing operation while the cakes are being formed

and which may be moved away from the cavities to open the same and permit the cakes to be ejected from the cavities by further movement of the plungers, thereby forming and ejecting the cakes by what is practically a single operation. Further, the movable bottom is preferably made in such a manner that when it is returned to its position beneath the plungers it will engage and discharge from the table the formed cakes which were previously ejected from the mold. Various mechanisms may be provided for accomplishing these results. In the present instance I have illustrated the invention as embodied in a form which has proven highly satisfactory in practice. This device comprises a table 1 having mounted thereon and depending therefrom a receptacle 2 adapted to contain the mass of material which is to be worked. Inasmuch as this material is usually warm to facilitate the handling and working thereof the receptacle is shown as having double walls to form a space 3 to contain warm water, a burner being arranged below the receptacle if desired. This receptacle is preferably mounted near one end of the table and on the opposite end of the table and adjacent to the receptacle is mounted the cake-forming devices proper which, as here shown, comprise a series of plungers 4 depending from a common support 5 which is in the form of a plate rigidly secured to upright members 6 slidably mounted on the table and held normally in their uppermost positions by means of springs 7. These upright members are provided at their lower ends with toothed racks 8 which mesh with segmental pinions 9 mounted on a common shaft 10 whereby the several plungers may be simultaneously moved downward against the tension of the springs 7. This movement of the plungers is accomplished by means of an actuating lever 11 rigidly secured to one end of the shaft 10 and preferably projecting toward that end of the table where the operator stands.

The mold which co-operates with the plungers to form the cakes, as above stated, comprises a plurality of cavities, one for each plunger. In the present form of the device I have shown the mold as comprising two parts. One part may be termed a mold plate, 12, having therein a plurality of cylindrical cavities 13 open at both ends and of a diameter slightly greater than the di-

diameter of the plungers 4, whereby when the cavities have been filled with material to be formed into cakes and placed beneath the plungers, the plungers may enter the 5 cavities and compress the material therein. The second part of the mold is a movable bottom plate 14 of a size substantially equal to the mold plate and adapted to be supported beneath the mold plate and close 10 to the under side thereof to close the bottoms of the several cavities. This bottom plate may be of any suitable character but as here shown it has a continuous upper surface and is provided on three sides with 15 depending flanges 15 which form supports therefor and enable the same to be moved over the surface of the table 1. It is also provided with stops or pins 16 to position the same with relation to the molding plate. 20 This latter plate is supported independently of the bottom plate while beneath the plungers and preferably at all times, although not necessarily so. In the present construction tracks 17 are arranged along the opposite 25 site sides of the table 1 and the end portions of the mold plate rest upon the respective tracks, the height of the tracks being such as to support the mold plate in proper relation to the bottom plate. As a result of 30 independently supporting the mold plate and making the bottom plate movable relatively thereto, as well as relatively to the plungers, I am enabled to utilize the plungers, first, to press the material in the mold 35 cavities into cake form and then by a further movement of the plungers to eject the material from the cavities.

In the operation of the device the bottom plate is withdrawn from beneath the 40 plungers into position above the receptacle 2 and when in this position it extends over a very considerable portion of the top of the receptacle and aids materially in preventing the too rapid cooling of the mass 45 of warm material within the receptacle. While in this position the mold plate is placed upon the same and filled from the receptacle. Either sufficient space may be left at the edge of the receptacle to afford 50 access thereto, or a dipperful of material may be removed from the receptacle before the bottom plate is entirely withdrawn. When all the mold cavities have been filled 55 the bottom plate is pushed into position beneath the plungers and the stops engaging the mold plate cause the same to move along the bottom plate. When the mold is in position beneath the plungers the lever 11 is manipulated to move the plungers down- 60 ward and cause the same to enter the mold cavities 13. In this connection it may be noted that means are provided for causing the mold cavities to be properly aligned with the plungers, thereby preventing the plungers from engaging the surface of the mold 65

plate and interrupting the operation of the device, if not causing injury thereto. A very simple and effective means is employed for this purpose which consists in providing near each end of the mold plate two or 70 more upwardly tapered alining devices or lugs 19, each of these devices being arranged adjacent to a mold cavity and the two devices at each end being arranged on opposite sides of the respective cavities. As a 75 result, should the mold plate be slightly out of alinement with the plungers when the latter are moved downward the plungers for the cavities having the alining devices will engage the inclined edges of these lugs 80 and will move the mold plate as a whole, bringing the remaining cavities into alinement with their respective plungers, this being accomplished automatically and without any interruption in the operation of the cake forming apparatus. The downward movement of the plunger is continued until the material has been compressed into a cake of the desired consistency. The movement of the plungers is then interrupted and the bottom plate 14 withdrawn, leaving the mold plate alone supported between the plungers and the table top 1. A further downward movement is then imparted to the plungers, causing them to eject the cake 90 or cakes from the mold cavities onto the table top. The lever is then released and the springs 7 elevate the plungers to their normal or idle positions. A mold plate, either the one which has just been used or 95 another one, is placed upon the bottom plate which is now in filling position, and is filled. The movement of the bottom plate and mold plate into position beneath the plungers to compress this new lot of material in the 105 cavities causes the forward edge of the bottom plate to engage the cakes which have previously been ejected from the mold cavities and to push the same from the table top onto an inclined chute 18 which may 110 lead either to a receptacle, traveling belt or any other suitable point. The formed cakes having been allowed to remain on the table top during the second filling operation have had an opportunity to set or 115 permit the binder to become sufficiently hardened to prevent any serious injury to be done to the cakes by the discharging operation. The mold having been again placed beneath the plungers the operation is 120 repeated as above described and is carried on in this manner until the mass of material in the receptacle is exhausted.

It will be noted that by means of this device it is necessary to handle the material 125 but once and that is when it is filled into the mold cavities. The compressing of the material into cake form and the ejecting of the formed cakes from the mold is accomplished by practically a single operation of the plun- 130

gers, the movement of the plungers being interrupted only long enough to permit the bottom of the cavities being opened by the withdrawal of the bottom plate. It is not necessary to remove the mold from the forming position and eject the formed cakes by a second operation, as is customary, nor is it necessary to gather up the formed cakes by hand, as has been customary heretofore, these being automatically discharged from the table by the return of the mold into forming position. Further, this construction enables the size of the table and the apparatus as a whole to be materially reduced, as it does away with the necessity of providing space for a second ejecting operation and for the handling of the parts that was necessary in former constructions. Moreover, the mold plates are automatically aligned with the plungers whenever they are within a reasonable distance of alignment and the bottom plate itself forms a closure in part, at least, for the open upper end of the material receptacle 2 and assists greatly in preventing the too rapid cooling of the mass of material therein.

While I have shown and described one embodiment of my invention it will be understood that this has been chosen for the purposes of illustration only, and that I do not desire to be limited to the details of construction, shown and described, for obvious modifications will occur to a person skilled in the art.

Having thus fully described my invention, what I claim as new and desire to secure by Letters Patent, is:—

1. A cake forming device comprising a table, plungers mounted above said table, a mold plate supported above and spaced a short distance from said table and having cavities to receive the material from which the cakes are to be formed, said cavities being open at both ends and said mold plate being movable to bring the cavities into alignment with the respective plungers, a bottom plate supported between said mold plate and said table to close the lower ends of said cavities, said bottom plate being movable in unison with, and in a direction parallel with the direction of movement of, said mold plate, to move the same into position beneath said plungers and being movable independently of said mold plate to enable it to be withdrawn from beneath said mold plate while the latter is in position beneath said plungers, and means to cause said plungers to enter the respective cavities in said mold plate and compress the material

therein while said bottom plate is in a position to close the lower ends of said cavities, and to cause said plungers to continue their movement in said cavities to eject the formed cakes onto said table after said bottom plate has been moved out of alignment with said cavities.

2. A cake-forming device comprising a table, a plunger mounted above said table, a mold plate supported between said plunger and said table and having a cavity to receive the material, said cavity being open at both ends, means to cause said plunger to enter one end of said cavity, a bottom plate supported between said mold plate and said table to close the other end of said cavity and movable relatively to said cavity and said plunger to permit the formed cake to be ejected from said cavity onto said table, said bottom plate and table being so arranged that when said bottom plate is again moved into position beneath said plunger it will engage the cake previously ejected and discharge the same.

3. A cake forming device comprising a table, a mold supported above said table and consisting of two parts, one of said parts having through and through openings therein forming molding cavities, the other of said parts being movable with and independently of the first-mentioned part and forming a closure for said openings when in one position relative thereto, said closure being movable into another position relative to said first-mentioned part to permit the cakes to be ejected from said cavities onto said table, and being arranged to engage the ejected cakes and discharge the same when returned to its first-mentioned position and plungers co-operating with said mold to form and eject the cakes.

4. A cake-forming device comprising a table, a receptacle supported by said table and having an open upper end, forming plungers mounted above said table at one side of said receptacle, and a mold movable into and out of a position beneath said plungers and comprising a mold plate and a bottom plate, said mold being so arranged that when it is in its outer or filling position said mold plate will be located above and close to the open upper end of said receptacle to partially close the same.

In testimony whereof, I affix my signature in presence of two witnesses.
